BAGGAGE RACK

Andrew T. Hagerty and Lemuel L. Stewart, Elkhart, Ind., assignors to The Adlake Company, a corporation of Illinois

Application December 31, 1937, Serial No. 182,857

9 Claims. (Cl. 240—7.35)

The principal object of this invention is to provide a baggage rack for cars, buses, ships and the like, of simple and strong construction that will receive and properly support lighting fixtures in suitable locations.

Generally speaking, the scheme of construction includes spaced brackets supporting rack bottoms, adapted to receive light fixtures for properly directing light downwardly on the seating area.

The invention lends itself to forms of sufficient variety to meet almost any condition or any personal desire of the buyer for architectural effect. A specimen that has met with favor is here chosen for illustration, but it is not intended to thereby impose unnecessary limitations on the claims.

A further object of the invention is to provide a combination baggage rack and lighting fixture which is suitable for use in cars having a wide variety of seating arrangements and which allows the location of the light box to be placed at any desired point in the bottom of the rack to afford the best possible distribution of light with relation to seats or other areas to be illuminated.

In the drawings—

Fig. 1 is a perspective view of a baggage rack embodying the invention, looking at it from below and with the left end thereof broken away;

Fig. 2 is a perspective view of a light fixture with the lid raised and parts broken away to show the interior;

Fig. 3 is a perspective view looking downwardly on the rack, the left end and intermediate portions being broken away to reveal the interior construction;

Fig. 3a is a perspective view of an end or cover plate;

Fig. 4 is a transverse section taken on the line 4—4 of Fig. 3;

Fig. 5 is a longitudinal vertical section of fragments of the basket rack including the right end, one intermediate bracket and a lighting fixture with portions of a rack bottom, the section being taken on the line 5—5 of Fig. 4;

Fig. 6 is a vertical transverse section taken on the line 6—6 of Fig. 3;

Fig. 7 is a longitudinal vertical section taken on the line 7—7 of Fig. 4, portion being broken away;

Fig. 7a is a fragmentary view showing the connection between the end bracket and the end rack section with the end plate applied;

Fig. 8 is a perspective view of an alternative

form of light fixture especially adapted for use with the ordinary bulb lamps;

Figs. 9 and 10 are sections taken on the lines 9—9 and 10—10 of Fig. 8 respectively.

5 The baggage rack is supported by several brackets spaced at suitable intervals and receiving between them the rack bottom sections. Intermediate brackets 10 are best shown in Figs. 1 and 3, where it appears that they have straddle legs 11, equipped with feet 12, through which screws, or bolts 13 pass into the side posts or some suitable reenforcements in the frame of the car, bus, ship, or the like.

End brackets 14, as best shown in Figs. 5 and 15 7, are like the intermediate brackets 10 except that portions of the feet 12 are cut away to make a closer fit against the adjacent wall or partition.

In the space between adjacent brackets there 20 is a rack bottom composed of front and rear bars 15 and 16, connecting and connected by a series of transverse ribs 17. The bars, in fact, are made of tubing and the ribs are made of bar stock, such as 10 B. W. gauge band iron, punched adjacent to the ends to receive the bars 15 and 16 and pressed to clamp them in place.

The rack bottoms are secured to the brackets 25 by rods 18 inserted through the tubes forming the bars 15 and 16 and, as shown in Figs. 5 and 7, each of the rods has one end reduced and threaded at 19 and the other drilled and tapped at 20 to correspond except at the right end of the rack as shown in Fig. 7a in which the rod has projecting studs at both ends. The rods 30 18 are slightly shorter than the tubes through which they pass, and hence, when connected together, and fastened to the end brackets by nuts 21, as shown, they serve to bind the whole 35 tightly together, clamping the rack bottoms between brackets.

The rack structure thus formed is dressed up and masked on the front by molding 22 of extruded aluminum. As appears best in Figs. 1, 3, 4 and 6, the molding has a bottom flange 23 45 that is positioned beneath the outer ends of the brackets 10 and 14 and the transverse ribs 17. To the right of this bottom flange is an upwardly inclined flange 24 and at the top of the molding is a hooked flange 25, near which, on the inside, is a shoulder or seat 9 adapted to receive the upper corner of the brackets.

Of course, molding can be secured in place in a great variety of ways, but for the sake of appearance it is preferably fastened from the 50 inside to the rack. As shown, this is done by

two sets of fastenings. The end of each bracket has a thickened portion 26 provided with a hole to receive a fulcrum pin 27, upon which is fulcrumed a fastening lever, or retainer bar 28, one at each side of the intermediate brackets and one at the inside only of the end brackets. Each of the levers has a hooked arm 29 cooperating with the hooked flange 25 and an oppositely directed arm 30 secured to the flange 24 by a screw 31. In the practical manufacture the fulcrum pins each have a knurled portion to be forced into the hole in the corresponding bracket.

Between the brackets the molding 22 is secured to the outer bar 15 of the rack bottom by means of a slightly different retainer bar, or lever 32 (Fig. 4) and a molding clamp 33. The bar 32 has hooked end 34 cooperating with the flange 25 and a laterally bent arm 35 cooperating with the outer bar 15 of the rack bottom. Obviously an arrangement similar to this could be used at the bracket in place of the lever 28 in order to avoid the necessity of drilling into the molding 22.

The molding clamp has one end 36 bearing against the outer side of the flange 24 and the other end 37 bent to bear on the lever 32 adjacent to a shoulder 38. The two parts are drawn tightly together by a screw 39 and act to bind the molding to the intermediate portion of the rack bottom as well as give stiffness to upper portion of the molding.

The outer side of the molding is here shown as having reed ribs 40, but it will be obvious that any kind of ornamentation and a great variety of shapes may be used in place of that shown.

Each end of the baggage rack is finished with a cast aluminum cover plate 41, secured to the outer side of the end bracket 14 by screws 42, received in thickened portions 43. Adjacent to each of those portions each plate has a pocket 44 to receive the nut or bolt at the end of the adjacent rod 18.

The structure thus far described makes a complete baggage rack that has found favor without regard to any lighting fixtures. It, however, lends itself very easily to combination with lighting fixtures carried by the rack bottom in a position suited to the seating arrangement.

The rack bottom used in this illustration provides rectangular spaces between adjacent transverse ribs 17 and is easily combined with lighting fixtures of generally rectangular form, shown in perspective in Fig. 2. Such a fixture includes a rectangular metal box 45 equipped at the bottom with a large light pane 46 that may be treated or constructed to distribute the light according to the scheme in use.

The top, or cover, 47 of the fixture is hinged at 48 so as to swing upwardly, as indicated in Fig. 2. This particular fixture is intended for use with tubular bulb lamps such as is illustrated at 49. Adjacent to the hinge 48 the lid is provided with a bracket 50 carrying a lamp socket 51 for the lamp 49.

Adjacent to its opposite end it is equipped with a spring clamp 52 to steady the otherwise free end of the lamp. Above or back of the lamp the cover is equipped with a suitable reflector 53 fixed to it by screws 54.

Adjacent to the bracket 50 another bracket 55 carries a socket 56 for a small blue lamp or night lamp 57.

The inner side of the lid, or cover, 47 is pro-

vided with a sheet of asbestos 58 and the outer side, or top, is provided with a metal shield 59 spaced from it by washers 60 far enough to permit circulation of air and to prevent direct transmission of heat.

The legs 11 of the brackets 10 and 14 straddle a metal conduit consisting of a flat plate 61 and a trough-shaped plate 62 spot welded together and secured to the wall by screws 63 and 64. Adjacent to each of the lighting fixtures there is an opening cooperating with an eyelet 65 at the rear end of the light box (Fig. 4) for the lead-in wires 66 and just above is an opening covered by plate 67 having legs straddling the box (Fig. 3) to provide access to the interior of the conduit. The wiring, of course, is a matter of choice and likewise the location of the switches but, for convenience, a switch for the present fixture is shown at 68.

Between the adjacent brackets there is fitted a piece of metal trim 69 having one flange (Fig. 4) 70 inserted beneath a turned up flange 71 on the conduit, and another flange 72 secured to the wall by screws 73. That gives the underside of the device a finished appearance, as indicated best in Fig. 1.

Tubular bulb lamps are more expensive than ordinary lamps and some users prefer the latter. They, however, require great depth of lighting fixture and a somewhat different structure, as illustrated in Figs. 8, 9 and 10. This modified fixture is also a rectangular metal box 74. The lid or cover 75, however, instead of being flat, as 47 in the other form, is arched as indicated at 76 in Fig. 10, to provide clearance for the larger lamps 77, and the arcuate reflector 78 is fitted into the arch.

The lamps 77 are mounted in sockets 79, carried by brackets 80, adjacent to each end of the cover. The shield 81 is provided with legs 82 having feet 83 spot-welded to the edges of the cover 75.

Both types of fixtures are held closed by screw fastening 84, swiveled in a lip 85 on the cover and engaging a bracket 86 on the end of the fixture.

Both types of fixtures are provided with shoulders 87, one adjacent to each corner, made by striking out a portion of the wall and inserting 50 a filler plate on the inside. These walls rest upon adjacent transverse ribs 17 in the rack bottom when the fixtures are in place, and they are fastened to the tubes 15 by arms 88, fixed to the shoulders by screws 89.

In installing the device in a car, the conduit is first applied, one end bracket is then put in place, two rods 18 are fastened to the bracket and one rack bottom assembly slipped over them, a second and intermediate bracket is installed, a second set of rods 18 inserted, and tightened up to put the proper amount of pressure on the first section of the rack. This procedure is repeated to the end of the car when the end plates are applied and the trim set in between the brackets. If light fixtures are used they are then inserted and the lead wires spliced to the main wires on the conduit channel. Finally, the front molding is applied in long lengths, usually two for each rack and the clamps set up. Of course, this procedure is suggestive and will necessarily be varied as variations in the construction are made.

Those skilled in the art will choose or design different forms of rack bottoms and different shapes and constructions of lighting fixtures to

suit various conditions and personal preferences. In following substantially the same construction shown, some will change the form of the light fixtures and let them project below the ribs 17, making the top of the fixture flush with the top of the ribs 17; some will make the ribs of substantially the same vertical depth as the fixtures, and so on.

The illustration, however, is deemed sufficient to show how the simple organization provides a rack or a combined basket rack and lighting fixture that is very adaptable.

We claim as our invention:

1. In a baggage rack, a rack bottom comprising front and rear parallel longitudinal edge members, means for supporting these members in spaced relation, a plurality of uniformly spaced transverse members carried by the front and rear longitudinal members, said bottom providing a plurality of adjoining similar substantially unobstructed open spaces each defined by two transverse members and the front and rear members, a lighting fixture comprising a lamp and casing therefor interchangeably fitting said spaces and supported by the rack in a certain selected one of said spaces and substantially filling said selected space.

2. In a baggage rack, a rack bottom comprising front and rear parallel longitudinal edge members, means for supporting these members in spaced relation, a plurality of uniformly spaced transverse members carried by the front and rear longitudinal members, said bottom providing a plurality of adjoining similar substantially unobstructed open spaces each defined by two transverse members and the front and rear members, and lighting fixtures comprising lamps and casings therefor interchangeably fitting said spaces and supported in certain selected ones thereof by engagement of the opposite sides of each casing with the transverse members defining the space occupied by said casing and substantially filling said selected spaces.

3. In a baggage rack, a rack bottom comprising front and rear parallel longitudinal edge members, means for supporting these members in spaced relation, a plurality of uniformly spaced straight transverse members carried by the front and rear longitudinal members, said bottom providing a plurality of adjoining similar substantially unobstructed open oblong spaces each defined by two transverse members and the front and rear members, and lighting fixtures comprising lamps and oblong casings therefor interchangeably fitting said spaces so as to substantially to close the same and supported in certain selected ones thereof so as to fill substantially completed said selected spaces.

4. In a device of the class described, a longitudinal box housing conduit containing electric wires, brackets extending outwardly from the conduit, a rack bottom comprising longitudinal front and rear edge bars carried by the brackets and a plurality of spaced transverse ribs carried by the front and rear bars extending generally parallel to the brackets and providing an unobstructed open space on each side of each rib defined by two ribs and the front and rear bars, and electric lighting fixtures comprising lamps and casings therefor interchangeably fitting substantially all of said spaces and supported by the rack in certain selected ones of said spaces, the casings abutting against a wall of the box

75 housing conduit and each lamp being connected to the wires in said conduit.

5. In a baggage rack, a longitudinal conduit containing electric wires and comprising a longitudinally extending box housing along the rear edge of the rack, a rack bottom comprising a rear longitudinal member adjacent to the conduit and a front longitudinal member, means for supporting these two members in parallel spaced relation, a plurality of uniformly spaced transverse members carried by the front and rear longitudinal members, said bottom providing a plurality of adjoining similar substantially unobstructed open spaces each defined by two transverse members and the front and rear members, the spaces terminating at the conduit, a lighting fixture comprising a lamp and casing therefor interchangeably fitting said spaces and supported by the rack in a certain selected one of said spaces on the transverse members defining same and substantially filling said selected space with one end disposed closely adjacent to the conduit and being connected to the wires in said conduit.

25 6. In a baggage rack, a longitudinal conduit containing electric wires, a rack bottom comprising a rear longitudinal member adjacent to the conduit and a front longitudinal member, means for supporting these two members in parallel spaced relation, a plurality of uniformly spaced transverse members carried by the front and rear longitudinal members, said bottom providing a plurality of adjoining similar substantially unobstructed open spaces each defined by two transverse members and the front and rear members, a lighting fixture comprising a lamp and casing therefor interchangeably fitting said spaces and having means overlapping said rack bottom for supporting the casing in a certain selected one of said spaces and substantially filling said selected space, the lamp being connected to the wires in said conduit, and locking arms secured to the casing and engaging beneath the front and rear longitudinal members.

45 7. In a baggage rack, spaced supporting means, longitudinal front and rear edge members carried by said means and each comprising a plurality of connected sections whereby the rack may be extended through any length of a vehicle body, a plurality of uniformly spaced transverse members carried by the front and rear members providing a plurality of adjoining similar substantially open spaces each defined by two transverse members and the front and rear members, and a plurality of similar lighting fixtures comprising electric lamps and casings therefor interchangeably fitting said spaces and supported in certain selected ones of said spaces and substantially filling said selected spaces and having shoulders integral with the sides of the casing engaged with certain of said transverse members whereby said casings are supported in certain selected ones of said spaces, and locking arms removably attached to the casing.

65 8. In a baggage rack, a rack bottom comprising a longitudinal element adapted to extend along and adjacent to the interior wall of a vehicle body, a second longitudinal element extending parallel to the first and spaced outwardly therefrom along substantially the outer edge of the rack, and a plurality of spaced parallel transverse elements connecting the longitudinal elements and providing a plurality of similar, generally oblong open spaces between adjacent trans-

verse elements, each of said spaces being bounded at its inner and outer ends by sections of the longitudinal elements, and a plurality of similar lighting fixtures comprising electric lamps and generally oblong casings therefor interchangeably fitting all of said spaces and supported by said elements in certain selected ones of said spaces.

9. In a baggage rack, a longitudinal conduit containing electric wires and comprising an elongated box housing forming the rear wall of the baggage rack, a rack bottom comprising a rear longitudinal member adjacent to the conduit and a front longitudinal member, means for supporting these two members in parallel spaced 10 15

relation, a plurality of uniformly spaced transverse members carried by the front and rear longitudinal members, said bottom providing a plurality of adjoining similar substantially open spaces each defined by two transverse members and the front and rear members, a lighting fixture comprising a lamp and casing therefor interchangeably fitting said spaces and supported by the rack in a certain selected one of said spaces and substantially filling said selected space, said casing abutting the lower portion of said rear wall, and the lamp being connected to the wires in said conduit.

ANDREW T. HAGERTY.
